UNITED STATES PATENT OFFICE.

WILLIAM W. SUTCLIFFE, OF NEW ORLEANS, LOUISIANA.

BAGASSE-FURNACE.

SPECIFICATION forming part of Letters Patent No. 400,016, dated March 19, 1889.

Application filed December 31, 1888. Serial No. 295,053. (No model.)

To all whom it may concern:

Be it known that I, WILLIAM W. SUTCLIFFE, a citizen of the United States, residing at New Orleans, in the parish of Orleans 5 and State of Louisiana, have invented new and useful Improvements in Bagasse-Furnaces, of which the following is a specification.

My invention relates to that class of steam-boilers and furnaces in which the heat is generated by bagasse and other waste material; and the purpose thereof is to simplify and improve furnaces of this class by providing the furnace-grate with air-tuyeres above and below, said tuyeres being supplied by manifolds located in the return-heat chamber of the furnace behind the bridge-wall, and in providing the fire-box or combustion-chamber with a reverberatory arch having a feed-opening in front of the boiler and a refractory fire-bed to aid the regeneration of the products of combustion and to reflect the heat to the forward part of the boiler.

The invention consists in the several novel features of construction and new combinations of parts hereinafter fully set forth, and then definitely pointed out in the claims, the said invention constituting certain improvements on the Letters Patent granted me September 18, 1888, and numbered 389,773 and 389,774.

In the accompanying drawings, Figure 1 is a front elevation showing my invention. Fig. 2 is a substantially central vertical section of Fig. 1 from front to rear. Fig. 3 is a horizontal section of Fig. 2 in the plane xx .

In the said drawings, the reference-numeral 1 denotes the wall of the furnace, within which is arranged a multitubular boiler, 2, of any desired pattern, partly supported by a bridge-wall, 3.

On the forward end of the furnace is built a combustion-chamber, 4, projecting from beneath the forward elevated end of the multi-tubular boiler 2. This chamber is provided with a reverberatory roof, 5, of arch shape, and has a rear wall, 6, from the top of which a refractory fire-bed, 7, extends to the top of the bridge-wall 3, said refractory fire-bed being 50 formed of iron or other suitable material.

In the rear of the bridge-wall 3 is a return-heat chamber, 8, within which I arrange transverse manifold pipes 9, communicating at one end with a tube, 10, which extends toward the combustion-chamber 4 and opens 55 into an air-chamber, 12, inclosed by a wall, 13, through which the pipe 10 passes. The other wall of this air-chamber is the rear wall, 6, of the combustion-chamber, which wall is provided with a number of air tuyeres or openings, 15, entering the fire-box above and below the grate of the latter. The air-chamber 12 also communicates by way of a passage, 16, beneath the fire-box, with a second air-chamber, 17, in the front wall inclosing the fire-box, said chamber 17 communicating by means of air-tuyeres 18 with the fire-box both above and below the grate. The pipes of the manifold 9 are connected to a cross-pipe, 19, which has a supply-pipe, 20, in which an air-current 70 is created by a blower, 21.

In this invention I employ no chamber in the bridge-wall and no flues leading from the combustion-chamber to the boilers. The heat is brought directly in contact with the heating-surfaces of the boiler, as shown in the drawings, and the refractory bed 7 reflects the heat to the forward part of the boiler.

A substantially central feed-passage, 22, is provided in the top of the combustion-chamber.

What I claim is—

1. A boiler-furnace for burning bagasse, consisting of the combustion-chamber having a reverberatory arch and extending longitudinally from the front wall of the furnace, the air-blast chambers located, respectively, at the front and rear of the combustion-chamber, communicating by a connecting-passage and provided with tuyere-openings located 85 above and below the fire-grate, a bridge-wall supporting the boiler, a refractory fire-bed inclined from above the rear air-blast chambers to the bridge-wall, an air-heater, and an air-forcer for forcing air through the heater into 90 one of the air-blast chambers, substantially as described.

2. In a bagasse-furnace, the combination, with a combustion-chamber having front and rear air-chambers provided with tuyeres en- 100

tering the fire-box above and below the grate, said air-chambers connected by a passage beneath the combustion-chamber, of a tube entering one of said air-chambers, passing 5 through the bridge-wall and into a return-heat chamber behind the bridge-wall, manifold pipes connected at one end with said tube and at the other end with an air-pipe,

and a blower supplying said air-pipe, substantially as described.

In testimony whereof I affix my signature in presence of two witnesses.

WM. W. SUTCLIFFE.
